UNITED STATES PATENT OFFICE.

HENRY M. SHEER, OF QUINCY, ILLINOIS.

OIL CONTAINER.

Application filed December 31, 1923. Serial No. 683,786.

To all whom it may concern:

Be it known that I, HENRY M. SHEER, a citizen of the United States, residing at Quincy, in the county of Adams and State 5 of Illinois, have invented certain new and useful Improvements in Oil Containers, of which the following is a specification.

My invention relates to metal oil containers for oil burning heaters and the like.

10 The object of my invention is to construct an oil container which is free from valves, and of such a construction that it can be tested under heavy pressure, and filled without danger of spilling oil on the floor or getting oil on the hands.

In the drawings:

Fig. 1 is a perspective view of the tank.

Fig. 2 is a longitudinal sectional view.

Fig. 3 is a transverse sectional view.

20 Fig. 4 is a transverse sectional view showing the inner tank in a reversed position.

Fig. 5 is a detail perspective.

The numeral 1 indicates the outer container provided with a removable cover 2, 25 and an outlet 3 at the bottom thereof. Rotatably journaled within the container 1, is a cylindrical container 4 journaled upon the rod, 5 extending longitudinally of the container 1. The outer end of the rod 5 is 30 in the form of a handle 6. The rotatable container is provided with an opening 7 centrally thereof.

The numeral 8 indicates a circular band of sufficient width to cover the opening 7.

35 This circular band is adapted to fit the container 4 snugly, and is provided at the top with a flared opening 9 which registers with the opening 7 in the cylindrical container 4.

An outlet 10 is provided at the bottom of the 40 band 8, the band 8 being prevented from rotating with the cylindrical container 4 by means of a cross-bar 11 secured in the bottom of the band and of sufficient length to contact with the walls of the outer container 1.

To fill the cylindrical container 4 the latter is turned to the position as indicated in Fig. 3 bringing the filling opening 9 of the band and the opening 7 of the cylindrical container into registration.

45 In case of any overflow the oil will flow into the outside container. After the cylindrical container 4 is filled it is turned one-half a revolution

bringing the opening 7 of the container into registration with the outlet 10 in the lower 55 side of the band 8, the oil feeding out into the outer container until it reaches the opening 10 sealing the latter. A very minute quantity of oil might escape during the turning operation, but not enough to be 60 noticeable, or in any way to affect the flow to the flame.

It will thus be seen that I have constructed a container free from valves, screens, or float mechanisms of any kind 65 which are liable to get out of order. Furthermore, the container can be manipulated and filled without danger of spilling oil on the hands, and one that will be neat in appearance, and more suitable and appropriate 70 for oil cook stoves, brooders and the like.

I claim:

1. A device of the character described including a stationary container, an inner container rotatably mounted in and carried by the stationary container, a band surrounding the inner container and carried thereby, and means for preventing the rotation of the band.

2. A device of the character described including a stationary container, an inner container rotatably mounted in and carried by the stationary container, a band surrounding the inner container and carried thereby, means for preventing the rotation of the band, and means extending from the ends of the inner container and connected with the stationary container for supporting the inner container within and by the stationary 80 container.

3. A device of the character described including an outer container, an inner rotatable container having an opening, a band surrounding said rotatable container and having filling and outlet openings adapted to register with the opening in the rotatable container, and a cross-bar secured to the band and adapted to engage the walls of the outer container to prevent the rotation of 95 the band.

4. An oil container comprising an outer stationary container, an inner rotatable cylindrical container mounted in said stationary container, and provided with a handle externally of the stationary con-

tainer for rotating the same, a circular band surrounding said rotatable container, a cross-bar affixed to said band adapted to contact with the walls of said stationary container to prevent the rotation of said band, said band being provided with a filling opening at its upper edge and an outlet

opening at the lower edge adapted to register with an opening in said rotatable cylindrical container when moved from its upper ¹⁰ to its lower position.

In testimony whereof I affix my signature.

HENRY M. SHEER.
